UNITED STATES PATENT OFFICE.

HERBERT W. SELLNER, OF FARIBAULT, MINNESOTA.

TOBOGGAN SLIDE AND TOBOGGAN.

Application filed November 19, 1925. Serial No. 70,048.

This invention relates to toboggan slides and toboggans where the toboggan is adapted to coast for some distance after leaving the end of the slide. The invention, as will be 5 hereinafter disclosed, is applicable either to water toboggans or toboggans or sleds adapted to run over ice and snow.

It is the main object of this invention to provide a toboggan slide and toboggan or 10 sled adapted to run thereon of simple but highly efficient construction provided with guide means for preventing both lateral or upward displacement of the toboggan from the slide.

It is a more specific object to provide a track or slide having rectilinear outer edges or flanges at the sides thereof, and a toboggan or sled mounted on wheels and having depending guide means at either side thereof, 20 disposed at the sides of said flanges of the slide, to prevent lateral displacement of the toboggan or sled therefrom.

It is an additional object to provide said depending guide means with inwardly extending lugs or heads adapted to underlie the outer rectilinear flanges of the track to prevent upward displacement or jumping of the toboggan from the track.

It is also an object of the invention to provide a highly efficient structure for mounting a plurality of relatively small wheels to project slightly below the bottom of the frame 30 of the toboggan.

These and other objects of the invention 35 will be apparent from the following description made in connection with the accompanying drawings, wherein like characters refer to similar parts throughout the several views, and in which

Fig. 1 is a side elevation of a portion of the slide or supporting surface with a form of the invention mounted thereon;

Fig. 2 is a cross section taken on the line 2—2 of Fig. 1;

Fig. 3 is a cross section on a larger scale taken on the line 3—3 of Fig. 1;

Fig. 4 is a plan view of one of the toboggans detached;

Fig. 5 is a side elevation of the preferred 50 form of the invention especially adapted for snow or ice toboggans;

Fig. 6 is a fragmentary cross section on a larger scale taken on the line 6—6 of Fig. 5;

Fig. 7 is a fragmentary vertical section 55 taken on the line 7—7 of Fig. 6; and

Fig. 8 is a plan view of this form of toboggan detached from the slide.

In the form of the invention illustrated in Figs. 1 to 4, inclusive, which form is especially adapted for use in water toboggans, a 60 flat runway or track is illustrated by the numeral 5 having the rectilinear outer flanges 5^a at either side thereof. Angle bars 6 covering the side and under surfaces of the flanges 5^a are preferably employed, although the 65 same may be omitted, if desired. The track 5 is supported by means of the parallel spaced and edgewise disposed inclined supporting members 7 mounted on standards 8, members 7 being connected at intervals by means of 70 the transverse bars 9 secured therebetween. A toboggan or sled, designated as an entirety by the letter A, is adapted to run or slide on the track 5 and compresses two pairs of longitudinal frame members or rails 10, with the 75 pairs of rails spaced from each other at either side of the toboggan and having up-turned forward portions. A plurality of spaced transverse ribs 11 are secured across the frame members 10 on the under side thereof, under 80 which members 11 a plurality of elongated slats 12 are secured having the upturned forward portions corresponding substantially to the shape of frame members 10. A rider's 85 platform is formed on the upper side of the toboggan by means of a plurality of straight slats 13 secured across the upper sides of transverse ribs 11 and falling short of the forward end of the frame members 10. The frame 90 members 10, at the outer sides of the toboggan, are provided with a plurality of longitudinally disposed slots 10^a providing hand 95 grips for the rider. Transversely aligned bearings are provided at the forward and rear ends of the frame secured to the under sides of the four frame members 10. These 100 bearings 14 are preferably in the form of maple blocks which have been previously soaked in oil. Between each pair of said bearings 14, a relatively short axle 15 is journaled having pinned or rigidly secured thereto to a wheel 16 projecting slightly below the bottom slats 12 and adapted to run on the track 5. Wheels 16, being keyed or rigidly secured to axles 15 and disposed between bearings 14 and the spaced frame members 10, 105 obviously prevent displacement of the axles 15 from the bearings.

Guide members are provided at either side of the toboggan A in the form of depending 110

L-shaped straps 17 secured at their upper ends to the outer frame members 10 and substantially aligned with the wheels 16, the extremities 17^a of said straps being inturned and spaced slightly below the under surfaces of flanges 5^a, while the main or inner surfaces are adapted to engage the outer edges of said flanges 5^a. The guide members 17 have their inner engaging surfaces slightly out turned or beveled to lessen the wear and friction on the sides of the flanges 5^a. The straps 17 may, of course, be secured to the toboggan adjacent or at the sides in any suitable manner, but preferably have their upper ends bolted or otherwise fastened to the outer frame members 10, their lower extremities depending below the wheels 16, and, as has been stated, slightly spaced from the under surface of the flanges 5^a.

In the preferred form of the invention illustrated in Figs. 5 to 8, inclusive, which is especially applicable to snow or ice toboggans, although capable of being employed in water toboggans, the track and supporting means therefor is similar to the modified form hitherto described. The track is, therefore, indicated by the numeral 5 having rectilinear outer flanges 5^a at either side thereof and supported by means of the parallel spaced and edgewise disposed supporting members 7 mounted on standards 8. The rectilinear outer flanges 5^a, however, preferably have relatively narrow strips or rails 18 secured to their top surfaces although the same may be omitted if desired.

The toboggan or sled indicated as an entirety by the letter B is constructed quite similar to the water toboggan previously described comprising two pairs of elongated spaced frame members or rails 19, one pair of the same being disposed at either side of the frame. These rails have upturned front portions and are secured together throughout their lengths by means of a plurality of spaced transverse ribs 20 on the under side thereof. An elongated frame member 21, having an upturned forward end, is secured to the under side of ribs 20 at each side of the sled B beneath the respective outer frame members 19 forming the runners of the sled or toboggan. A rider's platform is formed by means of a plurality of slats 22 secured across the upper sides of transverse ribs 11 and falling short of the forward end of frame members 19. Bearings 23 are provided, similar to the bearings 14 described in the modified form of the invention, secured to the undersides of the four frame members 19 and between said frame members and the runners 21. Wheels 24 are journaled in each pair of adjacent bearings and keyed or rigidly secured to axles 25. The wheels 24 are preferably provided with outer flanges 24^a adapted to engage the outer edges of the plates or rails 18. The runners 21, being disposed be-

neath the outer frame members 19, are adapted to extend at the sides of and in close proximity to the rectilinear edges of the flanged portion of the track, as shown in Fig. 6. Outwardly projecting lugs 26 are secured below each of the wheels 24 substantially vertically aligned therewith, and are adapted to be disposed beneath the flanged portions 5^a of the track in spaced relation thereto.

70

75

Operation.

The operation of both forms of the device is similar in most respects. The toboggan is carried to the top of the slide or incline and mounted thereon, grooves preferably being provided to permit the inturned edges of guide members 17 or lugs 26 to take their proper position beneath the flanges 5^a. The rider then takes his seat on the platform or deck formed by the slats and the toboggan will swiftly and smoothly descend the slide supported on its wheels, and will be prevented from lateral displacement from the track 5 by means of the depending members disposed at either side of track 5. In the preferred form, the runners of the sled constitute these depending members and, while the wheels of this form are provided with the flanges 24^a to engage rails 18, in case the toboggan attempts to leave the slide it will be prevented therefrom by means of engagement of the runners 21 with the side surfaces of the flanges 5^a of the track. Likewise, the toboggan or sled in either case will not be able to jump the track, being held to the flanged portions 5^a by means of the lugs 26, or, in the case of toboggan A, by means of the inturned flanges 17^a on the guide strips 17.

95

100

105

In the toboggan or sled B, the runners 21 will, of course, engage the surface of the snow or ice and permit the toboggan to coast thereover. Along the water toboggan A the smooth undersurface thereof, formed by means of the slats 12, will permit the toboggan to coast over the water a considerable distance after leaving the end of the slide.

110

The construction of the frame members of both forms of the invention and the mountings for the wheels hitherto described provides not only protection for the rider but an extremely smooth, freely running amusement device.

115

From the above description it will be seen that the applicant has invented a simple but efficient toboggan slide and toboggan capable of withstanding hard usage and equipped with novel means to provide a high degree of safety to the riders. Actual usage has shown the devices to be highly successful for the purposes intended.

120

It will, of course, be understood that various changes may be made in the form, details, proportions and arrangement of parts without departing from the scope of the invention.

125

130

What is claimed is:

1. In a toboggan slide the combination with an inclined track having flanged rectilinear outer edges, of a toboggan or sled comprising a frame having edgewise disposed elongated side members constituting ground engaging runners, wheels adapted to run on said track mounted in said frame inwardly of said runners and above the lower edges thereof, said runners being disposed outwardly of said track in close parallel relation to the side edges thereof, and inwardly extending means adjacent the bases of said runners adapted to underlie the side flanges of said track.
2. In a toboggan slide, the combination with an inclined track having flanged rectilinear outer edges, of a toboggan or sled comprising a frame having elongated side members, wheels adapted to run on said track 20 and mounted on said frame inwardly of said side members, substantially vertically disposed guide members carried by said side members and extending below the flanges of said track and inwardly extending members 25 adjacent the lower ends of said guide members adapted to underlie the flanges of said track and be spaced therefrom.

In testimony whereof I affix my signature.

HERBERT W. SELLNER.
